UNITED STATES PATENT OFFICE

ISIDORE SIMON, OF CHICAGO, ILLINOIS

SHOE

Application filed October 12, 1927. Serial No. 225,763.

This invention pertains to the general class of devices for correcting foot ailments. It is known that devices of this character have heretofore been produced; however, as far as 5 applicant is aware, no devices are in existence which embody the scientific principles as applied to shoes and their innersoles as disclosed in this application.

An object of the present invention is to prevent and correct abnormal distribution and abnormal direction of forces in the various parts of the human foot.

A further object of this invention is the production of devices, particularly shoes and 15 their innersoles, for preventing, correcting and checking undue strains and stresses and abnormal distribution of forces in and between the parts of the human foot, and for treating feet subjected to said abnormal 20 strains and stresses and forces.

A further object of this invention is a method for producing devices, particularly shoes and their innersoles, for the purpose of preventing, correcting, checking abnormal 25 strains and stresses and abnormal distribution of forces in the human foot and for treating feet subjected to other than normal forces.

A further object of this invention is the production of apparatus for producing devices, particularly shoes and their innersoles, for the purpose of preventing, correcting and 30 checking abnormal strains and stresses and abnormal distribution of forces in the human foot and for treating feet subjected to abnormal 35 forces.

Many other objects and advantages of the construction herein shown and described will be obvious to those skilled in the art from the 40 disclosure herein given.

To this end my invention consists in the novel construction, arrangement and combination of parts herein shown and described, and more particularly pointed out in the 45 claims.

In the drawings, wherein like reference characters indicate like or corresponding parts:

Fig. 1 is a sectional elevation of a shoe illustrating the invention;

Fig. 2 is a top plan view of an innersole adapted for a left foot;

Fig. 3 is a fragmentary section taken on line 3—3 of Fig. 1 illustrating the position of the boss;

55

Fig. 4 is a section on the line 4—4 of Fig. 1;

Fig. 5 is a fragmentary top plan view of the heel portion of an innersole with the top layer removed to show the position of the wedge and concavity;

60

Fig. 6 is a view in which the concavity at the heel is adapted to an ordinary shoe;

65

Fig. 7 is a different form of the invention showing a concavity for the lateral as well as the median tubercle.

Fig. 8 is a top plan view of the last;

Fig. 9 is a longitudinal section of a last with innersole applied thereto, the direction being indicated by the arrows on line 9—9 of Fig. 8;

70

Fig. 10 is a transversal section of the last shown in Fig. 8 with an innersole applied thereto indicated by line 10—10;

Fig. 11 is a section on line 11—11 of Fig. 8, and in addition thereto showing the position of the wedge, the concavity at the heel and 75 the split innersole;

75

Fig. 12 is a detail view of the wedge; and

Fig. 13 is a top plan view of a different form of the invention illustrating a depression in an innersole for the lateral tubercle of 80 the oscilis as well as the median tubercle.

In a preferred form of the invention, the inner sole 25 (see Fig. 2) is embossed at 26 before being applied to the last, to form a counterbalance for the base of the fifth metatarsal bone of the foot, the base being a weight bearing point of the outer component part of the foot. The innersole is then split into upper part 38 and lower part 37 (see Fig. 11) from heel to shank and a leather wedge 27 inserted or a filler at the inner side of the heel otherwise provided, its greatest thickness being on the medial or inner side of the foot. The purpose of this wedge or

85

filler is to counterbalance the lateral tubercle of the oscilis located in the outer component part of the foot. Cooperative with the wedge 27 and the boss 26 is the U-shaped or semi-circular cut-away portion 28 (see Figs. 5 and 12). Cooperating therewith is 95

90

95

100

the concave depression 29. One of the purposes of parts 28 and 29 is to obtain a proper and perfect support at the heel, particularly on the medial side of the center line. The parts 28 and 29 receive the median tubercle of the foot. This allows the wedge 27 to extend at least to the center line or further if desired in order that the proper angle and support at the heel may be obtained in aggravated and especial cases. However, in the preferred embodiment, the transverse inclined plane originates at the center line. The parts 28 and 29 furthermore relieve the median tubercle of undue strain and stresses with attendant tenderness and soreness so common when ordinary shoes are worn and particularly shoes of this general character. The pressure on the tip of the tubercle is obviously greatly reduced or relieved entirely and the weight is carried over a much larger surface above and immediately surrounding the tubercle. It is obvious that other shapes of supports may be substituted for the wedge 27, the wedge being merely the preferred embodiment.

The innersole 25 is embossed before being applied to the last. The embossed portion 26 is held in place by a boss 30 being formed of vulcanized rubber or other plastic substance. Its *general* shape approximates an ellipse, flat on one side and convex on the other. It is cemented into the concavity formed in the under surface of the innersole due to the embossing and is then covered with canvas or other suitable material 31 and secured in place.

The innersole thus formed with mathematical precision is to be incorporated into all sizes and styles of foot wear, the boss being maintained by a vulcanized or other plastic compound.

A new method of making shoes is thus provided in which the inner sole forms a geometrical counterbalance for the weight bearing points of the outer component part of the foot. The embossed portion 26 and wedge 27 form the weight bearing points for the inner component part of the foot, the boss 30 and wedge 27 occurring in the inner sole proper, leaving the interior side of the innersole a plain flat surface covered with canvas or other suitable material 31 interfering in no way with the channeling of the innersole, and not depending in any way upon the cork-gum filler 32 used in shoe construction to support or maintain the boss 30 or the wedge 27. The outer sole is shown at 33, the heel of the shoe at 34 and the upper at 40.

The invention may be carried out on a last 35 with a depression as at 36 (Fig. 8) to receive the innersole with the embossed portion 26, the greatest elevation of which is located at a point on the center line of the foot opposite the shafts of the second and third meta-

tarsal bones, respectively, at the junction of their medial and distal thirds. At this point is formed one angle of an isosceles triangle, the base and head of the fifth metatarsal bone being the other two points, the base of the triangle extending from the point of juncture mentioned above to the head of the fifth metatarsal. This formation of the depression 36 is accomplished by tooling out the last to accommodate the embossed portion 26 on the innersole.

The last is further formed with an elevation or boss 39 located approximately centrally of the heel portion. This elevation or boss-like formation fits into the concavity of the depression 29 in the heel seat of the innersole.

The heel of the last is further shaped to receive the elevation on the innersole caused by the wedge by cutting down the wood of the last shown at 41, forming two inclined planes 41 and 42, the plane 41 with its lower point located at the medial or inner border and its highest point terminating at the center line (see Fig. 8), and the longitudinal inclined plane 42 with its lowest point located at the posterior border 43 of the heel and terminating at the junction of the heel 44 and shank 45 with the exception of an additional elevation 39 at a point located beneath the median tubercle of the oscalsis to fit into the concavity or depression 29 on the heel seat of the innersole previously set forth.

It is obvious that as a modification of the applicant's invention, a thick innersole 100 may be employed and instead of inserting a wedge on the innerside, the outer side may be cut away.

Fig. 6 shows a modification of applicant's invention showing the depression 50 at the heel for the medial tubercle of the oscalsis applied to the ordinary shoe.

Fig. 7 is a further modification in which a depression 46 is further provided for the lateral tubercle of the oscalsis. This form is preferable in many instances, inasmuch as the depression for the lateral tubercle is equivalent in certain respects to a slightly higher wedge. Furthermore, the depression relieves undue strain on the lateral tubercle. The last for making this form is further provided with an elevation or boss opposite the lateral tubercle.

Fig. 13 is a top plan view of an innersole showing the position of the depression 46 for the lateral tubercle of the oscalsis.

Having thus described my invention, it is obvious that various immaterial modifications may be made in the same without departing from the spirit of my invention; hence I do not wish to be understood as limiting myself to the exact form, construction, arrangement and combination of parts herein shown and described, or uses mentioned.

What I claim as new and desire to secure by Letters Patent is:

1. In a shoe in combination, an inclined support for the oscalsis at the side opposite the side of the lateral tubercle of the oscalsis having its highest elevation at the inside edge of the heel, and a depression in the floor of the inner sole in the heel portion thereof opposite the median tubercle of the oscalsis.

2. In a shoe, in combination, a depression in the heel portion of the innersole thereof, said depression to receive the median tubercle of the oscalsis when the shoe is worn, and a second depression in the heel portion of said innersole, said second depression to receive the lateral tubercle of the oscalsis.

3. In a shoe in combination, means for counter-balancing the base of the fifth metatarsal, an inclined support for the medial side of the oscalsis having its highest elevation at the inside edge of the heel, and a depression to receive the median tubercle of the oscalsis.

4. In a shoe in combination, a support for the metatarsal bones, an inclined support for the medial side of the oscalsis having its highest elevation at the inside edge of the heel, and a depression to receive the median tubercle of the oscalsis.

5. In a shoe in combination, a support for the forward part of the foot, an inclined support at the heel thereof with its highest elevation at the inside edge of the heel and a depression in the innersole in the heel portion thereof spaced from the edges a predetermined distance, said depression to receive the median tubercle of the oscalsis.

6. In a shoe in combination, a support for the forward part of the foot, an inclined support at the heel thereof with its highest elevation at the inside edge of the heel, the innersole having a depression in the heel portion thereof, said depression to receive the median tubercle of the oscalsis, and a second depression in the innersole in the heel portion thereof, said second depression to receive the lateral tubercle of the oscalsis.

7. In a shoe in combination, means for counterbalancing the base of the fifth metatarsal, a support for the oscalsis on the side opposite the side of the lateral tubercle of the oscalsis, said latter support having its highest elevation approximately at the inner rear portion of the heel and defining two inclined surfaces, one sloping laterally toward the outer side of the shoe, the other sloping toward the front of the shoe, and a depression in the innersole to receive the median tubercle of the oscalsis.

8. In a shoe in combination, a support for the metatarsal bones, a support for the oscalsis on the side opposite the side of the lateral tubercle of the oscalsis, said latter

support having its highest elevation approximately at the inner rear portion of the heel and defining two inclined surfaces, one sloping laterally toward the outer side of the shoe, the other sloping toward the front of the shoe, and a depression in the inner sole to receive the median tubercle of the oscalsis.

In testimony whereof, I have hereunto signed my name.

ISIDORE SIMON.
